(57) **CLAIM**

I claim the ornamental design for a bottle, as shown.

DESCRIPTION

FIG. 1 is a bottom, front perspective view of a bottle showing my new design. It is understood that the bottle is transparent, however, the opposing side has not been shown for ease of illustration;

FIG. 2 is a front elevational view thereof;

FIG. 3 is a side elevational view thereof;

FIG. 4 is a bottom plan view thereof; and,

FIG. 5 is a top plan view thereof.

1 Claim, 4 Drawing Sheets
